AMBULANCE STRETCHER

Basil Monk, Croydon, England, assignor to Tor Equipment Company Limited, Croydon, England, a British company

Application December 7, 1934, Serial No. 756,437
In Great Britain April 14, 1934

11 Claims. (Cl. 5—82)

This invention relates to ambulance stretchers, and the object of the invention is to provide means for supporting a patient on a stretcher of conventional design in such a way as to permit a loaded stretcher to be tilted in any direction thus enabling a stretcher with a patient thereon to be carried otherwise than in the normal horizontal position and to be passed through constricted passages or other spaces.

10 The invention provides the combination with an ambulance stretcher comprising side poles and a canvas or other bed, of auxiliary means for supporting a patient thereon comprising a plurality of flexible members, for example straps or the like, or a flexible cover, or a combination of both, located by one of the stretcher poles and adapted to bridge from one pole to the other over the patient's body and thereby to permit the stretcher when loaded to tilt or to be tilted sidewise and/or 20 endwise while at the same time the patient is adequately supported.

The invention also includes an attachment for an ambulance stretcher, comprising for example a bar which is of a length comparable with that 25 of the stretcher poles and which is provided with means for locating the bar alongside one of the poles and anchoring it to said pole at intervals therealong, said locating-means comprising a number of clips on the bar which are spaced apart 30 lengthwise thereof and by which the bar may be readily attached to the pole, and a plurality of flexible members arranged to provide a means of supporting a patient on the stretcher substantially in the manner hereinafter described so as to 35 permit the stretcher when loaded to be tilted, or to be carried otherwise than in the normal horizontal position.

The invention further includes features which are concerned with constructional details and 40 which will be fully described hereinafter and specifically pointed out in the appended claims.

One constructional form of the invention applied to an ambulance stretcher of conventional design will now be described, by way of example, 45 with reference to the accompanying drawings in which:—

Figure 1 is a plan of an attachment according to the invention.

Figure 2 is a transverse section on the line 2—2 50 of Figure 1 drawn to a larger scale.

Figure 3 is a detail plan, drawn to the same scale as Figure 2, of a part of the attachment.

Figure 4 is a detail view showing one of the 55 straps ready to be mounted on one of the stretcher poles.

Figure 5 is a perspective view showing a patient supported on a stretcher, and

Figure 6 is a perspective view showing the attachment removed from the stretcher and folded up for transport.

Like reference numerals indicate like parts throughout.

The stretcher, which is shown in chain lines on the drawings, comprises the usual side poles 10, 11 which are square in cross-section, except at the ends where they are shaped to form handles for carrying purposes, and legs 12, the legs at each end of the stretcher being connected by a foldable bar 13 to permit the stretcher to be collapsed. The poles are also connected by a canvas 15 bed 14.

The attachment which is provided, according to the invention, for the purpose described is a unit comprising a rigid circular bar 15 of a length about equal to that of the stretcher bed. Mounted on this bar at intervals are three substantially L-shaped metal clips 16, 17, 18. These clips are mounted on the pole 10 and are arranged so that when so mounted the vertical limbs of the clips will lie against the outer face of the pole and the horizontal limbs will bear against the underside of the pole. The upper end of the vertical limb of each clip is bent inwardly and then outwardly to provide an eye 19 in which the bar 15 is received, and the inner end of the horizontal limb is bent 30 upwardly as shown at 20 to prevent the clips from being accidentally detached from the pole. Three straps 21, 22, 23 are riveted each at one end to the underside of the horizontal limbs of the clips 16, 17, 18 respectively. The said ends of the straps 35 are connected each by a ring 24 to buckles 25, 26, 27 respectively, each buckle being movable around its ring for the purpose hereinafter explained. Each of the straps 21, 22, 23 is of a length to permit it to be passed under the stretcher bed around 40 the other pole and backwardly over a patient on the stretcher and then to be fastened to one of the buckles aforesaid.

The clips 16, 17 are so arranged that the straps 21, 22 will be adjacent to the body of a patient on the stretcher, and the clip 18 is so positioned that the strap 23 will be adjacent to the feet of the patient. The strap is provided with a loop 28 to receive the patient's feet.

A flexible cover 29, for example made of canvas is provided for the patient and is arranged so as to permit it to be secured closely over the patient by the straps. For this purpose the cover is hemmed along one longitudinal margin to pro- 50 55

vide a pocket 30 in which the rigid bar 15 is received. The eyes 19 of the clips are positioned in recesses 31, see especially Figure 3, in said margin of the cover. The recesses 31 are of such a length that the ends thereof will serve to prevent any substantial movement of the clips 16, 17, 18 along the bar 15 should the eyes 19 be loose on said bar. One end of the pocket 30 is permanently closed and the other end is arranged to be closed by a flap 32, a press button fastener 33 being provided for holding the flap in closed position. The longitudinal margin of the cover opposite to that provided with the pocket 30 is also hemmed to provide a pocket 34 in which a stiffener in the form of a circular metal bar 35 is received. One end of this pocket is also permanently closed, and the other end is arranged to be closed by a flap 36 in a similar manner to that described with reference to the pocket 30. If for any reason it is desired to remove the stiffener bar 35 from the pocket 34, say to permit that side of the cover to be folded up to suit the convenience of a patient, said bar can be inserted in the pocket 30 which is made large enough for this purpose, thus preventing the bar 35 from being mislaid.

The cover 29 is provided with a number of guide loops for the straps arranged to permit the straps to be fastened in a taut condition across the patient in different directions at will. In 30 the construction shown on the drawings these guide loops are arranged in three rows longitudinally of the cover, namely, one side row consisting of three loops 37, 38, 39, an intermediate row consisting of loops 40, 41 and another side row consisting of loops 42, 43, 44.

A rest 45 of substantially U-shape in cross section is provided for the head of the patient. This head-rest is detachably mounted on the bed of the stretcher by means of a strap 46 which is attached at one end to one side of the head-rest and is of a length sufficient to permit it to be passed under the stretcher and around the pole at the other side of the head-rest. The strap 46 is provided at this end with a buckle 47 whereby 45 it can be connected to a short strap 48 which is fixed intermediate of its ends to the head-rest and carries at its other end a buckle 49. A band 50 is attached to the same side of the head-rest as the strap 46 and is adapted to be drawn taut 50 across the patient's forehead and to be connected to the buckle 49 to hold the patient's head in position on the head-rest. It will be appreciated that the U-shaped head-rest will provide support 55 for the patient's head when the stretcher is tilted sidewise in either direction and that the band will support the head when the stretcher is upended. By unfastening the band 50 from the short strap 48, the patient can be removed without detaching the head-rest from the stretcher.

60 Figure 5 shows one way of fastening the straps so as to hold a patient on the stretcher and provide adequate support for him in whichever direction the stretcher may be tilted. In this arrangement, the cover 29 is first drawn closely over the patient. The strap 22 is then passed under the stretcher, around the pole 11, and obliquely across the patient through the loops 43 and 40 and finally is drawn taut and secured to the buckle 25. The strap 21 is similarly passed under the stretcher, round said pole, and through the loops 42 and 40, and is secured in a taut condition to the buckle 26. The foot strap 23 is passed under the stretcher, around the pole 11 through 70 the loop 44 over the patient's feet so that they

lie in the loop 28, through the loop 39 and is then drawn taut and attached to the buckle 27. As the buckles 25, 26, 27 are movable around the rings 24 the straps can be fastened obliquely across the patient without any appreciable 5 twisting. If the patient is wearing shoes, the heels thereof will serve to position the strap and prevent it from slipping downwardly, while the inner branch of the loop 28 will prevent the patient from drawing his feet upwardly away 10 from the outer branch of that loop. A stretcher with a patient held thereon in this manner can be tilted sidewise or upended in either direction without any discomfort to the patient and without any risk of the patient slipping off the 15 stretcher even if it is turned into a vertical position. The clip 18 will usually be situated only a short distance from the legs and foldable cross bar 13 at the foot end of the stretcher, and they will serve to prevent any substantial slipping of 20 the attachment downwardly when the stretcher is upended feet downwards. Usually, if it is necessary to upend the stretcher, the patient will be carried or lowered feet downwards but if exceptional circumstances arise he can even be 25 carried or lowered head downwards without risk of slipping off the stretcher.

If it is desired to transport the attachment, it is only necessary to remove the clips 16, 17, 18 from the pole 10, which can easily be effected as 30 no fastening means is necessary for these clips, and then to roll up the cover in said clips. When thus rolled up the cover can be held therein by means of the straps 21, 22 and 23 as shown in Figure 6.

35 The invention is not restricted to the specific constructional details described and shown on the drawings, as many modifications may be made therein without departing from the invention, nor to the particular manner of fastening 40 the straps as that may be determined by the patient's injuries, wounds or other factors.

I claim:—

1. An attachment for an ambulance stretcher having side poles and a bed, comprising a bar 45 of substantially the same length as the bed of the stretcher, a number of clips on said bar for attachment to one of the stretcher poles, and a number of flexible members and fasteners therefor, each clip having a flexible member and a 50 fastener anchored thereto, which flexible members are of a length sufficient to permit each to be passed under the stretcher bed around the other pole and backwardly over a patient on the stretcher and then to be secured to one of the 55 fasteners.

2. An attachment for an ambulance stretcher having side poles and a bed, comprising as a unit a bar of substantially the same length as the bed of the stretcher, a number of clips on said bar for attachment to one of the stretcher poles, a number of body straps and buckles therefor, each clip having a strap and a buckle anchored thereto, which straps are of a length sufficient to permit each to be passed under the stretcher bed 60 around the other pole and backwardly over a patient on the stretcher and then to be fastened to one of the buckles, and a foot strap positioned along the stretcher so that it will be adjacent to the feet of a patient thereon, which foot strap 65 is provided with a loop to receive the patient's feet.

3. The combination with an ambulance stretcher comprising side poles, of a strap-carrier in the form of a bar means for connecting the bar to 70 75

5 one of the stretcher poles, a plurality of straps anchored to the strap-carrier and situated at intervals along said carrier and adapted to extend across the bed of the stretcher from pole to pole and to be secured in a taut condition to enable the stretcher to be tilted while still affording adequate support for a patient thereon, and a cover for the patient carried by said bar.

10 4. An attachment for an ambulance stretcher having side poles and a bed, comprising as a unit a bar of substantially the same length as the bed, a number of clips on said bar for attachment to one of the stretcher poles, a buckle attached to each clip, a cover for the patient provided along 15 one longitudinal margin with a pocket in which said bar is received, and a number of straps attached to said clips, which straps are of a length sufficient to permit each to be passed under the stretcher bed, around the other pole and backwardly over the cover when the latter is drawn closely over the patient and then to be fastened to one of the buckles so as to hold the cover in position on the patient and the latter on the stretcher when it is carried otherwise than in the 20 normal horizontal position.

25 5. An attachment for an ambulance stretcher as claimed in claim 4, wherein recesses are provided in said longitudinal margin of the cover to receive the clips aforesaid, the ends of which recesses serve to prevent any substantial movement of the clips along the bar.

30 6. An attachment for an ambulance stretcher having side poles and a bed, comprising as a unit a bar of substantially the same length as the bed of the stretcher, a number of clips on said bar for attachment to one of the stretcher poles, a number of straps and buckles therefor for holding a patient on the stretcher when the latter is tilted, each clip having a strap and a buckle anchored thereto, and a flexible cover for the patient, which cover is mounted along one of its longitudinal margins on the said bar and is provided with a stiffener along its other longitudinal margin.

35 45 7. An attachment for an ambulance stretcher having side poles and a bed, comprising as a unit a bar of substantially the same length as the bed of the stretcher, a number of clips on said bar for attachment to one of the stretcher poles, a number of straps and buckles therefor for holding a patient on the stretcher when the latter is tilted, each clip having a strap and a buckle anchored thereto, a flexible cover for the patient, which cover has along one longitudinal margin a pocket 40 in which said bar is received and along its other longitudinal margin a second pocket, and a removable stiffener in said second pocket, the pocket in which said bar is received being large enough to accommodate also said removable stiffener. 45

50 60 when the latter is not required for use as a stiffener.

8. An attachment for an ambulance stretcher comprising as a unit a bar to extend lengthwise along one of the stretcher poles, a number of clips on said bar for connecting it to said pole, a number of straps and buckles therefor for holding a patient on the stretcher when the latter is tilted, each clip having a strap and a buckle anchored thereto, and a cover for the patient having on the outside a number of guide loops for the straps arranged to permit the straps to be 10 fastened in a taut condition across the patient in different directions at will.

15 9. For an ambulance stretcher comprising side poles and a flexible bed connecting them, an attachment comprising a bar of substantially the same length as the bed of the stretcher, a number of clips on said bar for attachment to one of the stretcher poles, a flexible cover for the patient and a number of straps for holding the cover in position on the patient and the 20 patient on the stretcher when the latter is tilted, which clips are adapted when detached from the stretcher to accommodate the cover when rolled up and in which clips the rolled-up cover can be held by the straps.

25 10. An attachment for an ambulance stretcher comprising a bar which is of a length comparable with that of the stretcher poles and which is provided with means for locating the bar alongside one of the poles and anchoring it to the said 30 pole at intervals therealong, said locating means comprising a number of clips on the bar which are spaced apart lengthwise thereof and by which the bar may be readily attached to the pole, and a plurality of flexible members attached to the 35 clips and arranged to provide a means of supporting a patient on the stretcher so as to permit the stretcher when loaded to be tilted, or to be carried otherwise than in the normal horizontal position.

40 11. An attachment for an ambulance stretcher comprising a bar which is of a length comparable with that of the stretcher poles and which is provided with means for locating the bar alongside one of the poles and anchoring it to the said pole 45 at intervals therealong, said locating means comprising a number of clips on the bar which are spaced apart lengthwise thereof and by which the bar may be readily attached to the pole, a plurality of flexible members attached to the clips 50 and arranged to provide a means of supporting a patient on the stretcher so as to permit the stretcher when loaded to be tilted, or to be carried otherwise than in the normal horizontal position, and a cover for the patient mounted on the 55 bar along one longitudinal margin thereof and arranged to permit it to be secured over the patient by the flexible members.
